(57) **CLAIM**

The ornamental design for a golf club head for a putter with red pattern, as shown and described.

DESCRIPTION

The file of this patent contains at least one drawing executed in color. Copies of this patent with color drawings will be provided by the Office upon request and payment of the necessary fee

FIG. 1 is a front view of a golf club head for a putter with red pattern showing our new design; and,

FIG. 2 is a top perspective view thereof.

The pattern shown in FIG. 1 is colored red. The broken line showing that is immediately adjacent to the shaded area represents an unclaimed boundary and forms no part of the claimed design. The broken line showing of the remainder of the golf club head for a putter is for illustrative purposes only and forms no part of the claimed design.
